METAL SPINNING APPARATUS

John W. Shera, Shaker Heights, Ohio, assignor,
by mesne assignments, to American Flange &
Manufacturing Co., Inc., New York, N. Y., a cor-
poration of Illinois

Application December 9, 1939, Serial No. 308,406

4 Claims.

(Cl. 113—19)

The invention relates to metal spinning and more particularly to an apparatus for securing preferably a sheet metal collar to, and externally of, a sheet metal neck projecting from a metal wall of a metallic container.

The C. T. Draper Patent No. 2,156,237 shows an integral threaded metallic container bung opening neck having a surrounding flanged collar and this construction has heretofore been made by first pressing the flanged collar on the neck in a press and by then transferring the article to a spinner and spinning a flange on the neck to secure the flanged collar thereto.

The securing of such flanged collar therefore requires two separate operations with intervening handling. In the manufacture of metallic containers a reduction in cost, by the elimination of any one or more operations, may result in a substantial relative saving.

It is therefore a principal object of the present invention to reduce the cost of metallic container construction by eliminating one operation, and the handling incident thereto, involved in securing a flanged collar to an integral threaded bung opening neck of the type generally shown in the Draper Patent No. 2,156,237.

It is a further object of the present invention to provide an improved pressure spinning tool for positively pressing a collar on a neck by alternating yielding and positive pressure and simultaneously spinning an outturned lip or flange on the outer end of the neck to secure the collar thereto.

When a collar is secured to a neck by two operations with intervening handling, the collar may become tilted or displaced from proper position on the neck after the pressing operation and during the intervening handling so that a subsequent spinning operation may make an imperfect article.

It is therefore a further object of the present invention to provide an improved pressure spinning tool for securing a collar to a neck, the operation of which insures the proper or exact positioning of the collar on the neck when secured thereto.

It is a further object of the present invention to provide an improved pressure spinning tool for securing a collar to a neck including an external non-rotating pressure sleeve for telescoping the collar over the neck and spinning means disposed within the sleeve for spinning the upstanding neck outwardly at its upper edge over the collar.

A further object of the present invention is to provide an improved pressure spinning tool of the character and for the purpose just described having a plurality of spinning rollers whose axes are parallel to the axis of the sleeve whereby the spinning rollers may be readily mounted in the

confined space with a minimum deflection or tilting thereof during operation.

Moreover, it is an object of the present invention to provide an improved pressure spinning tool of the character and for the purpose just described having a pilot in advance of both the pressure and spinning means for centering the pressing tool as it completes its operation and for guiding the entry of the spinning means into the neck.

Moreover, it is an object of the present invention to provide an improved apparatus for securing a flanged collar externally to a threaded bung opening neck by a single machine operation, by first yieldingly and then positively pressing a collar onto a neck, the collar telescoping over the neck, then yieldingly holding the collar on the neck while simultaneously spinning a lip on the neck over the collar, and finally positively pressing the collar on the neck as the spinning is completed.

And finally, it is an object of the present invention to provide an improved apparatus for securing a collar to a threaded bung opening neck which apparatus may be employed with any one of a number of standard types of drill presses.

The above and other objects may be obtained by the improved apparatus, elements, parts, combinations and constructions which constitute the present invention, a preferred embodiment of which is shown in the drawings and is hereinafter claimed and described in detail, may be stated in general terms as including in a pressure spinning tool, a pressure sleeve holder, removably secured to or formed as an integral part of the non-rotatable quill of a drill press or similar machine tool, pressure sleeve means non-rotatably slidably mounted on the pressure sleeve holder, adjustable means limiting relative movement in each direction between the pressure sleeve holder and the pressure sleeve means, compression springs or other yielding means normally holding the pressure sleeve means in an extended position, a preferably annular pressure foot formed as a part of or attached to the extended end of the pressure sleeve means; a spinning head removably mounted on or formed as a part of the rotatable machine tool spindle, a plurality of spinning rolls mounted on said spinning head within said pressure sleeve means, the axes of the spinning rolls preferably being parallel to the axis of the spindle and the working surfaces of the spinning rolls being located substantially entirely within the opening defined by the annular pressure foot and being normally located above the extended position of the pressure foot, and preferably a cylindrical pilot secured to the spinning head concentrically of the spinning head and pressure foot normally located in a position below the pressure foot and spinning

rolls and preferably maintaining the spinning rolls assembled in the head.

In the drawings—

Figure 1 is an axial section through the improved pressure spinning tool in the position which the tool parts assume upon completing a collar seating and neck spinning operation;

Fig. 2 is a transverse section taken on the line 2—2, Fig. 1;

Fig. 3 is a fragmentary axial section taken on the line 3—3, Fig. 2, with the parts in the same position as in Fig. 1;

Fig. 4 is a bottom end view of the improved pressure spinning tool looking in the direction of the arrows 4—4, Fig. 1 with the work removed, certain parts being broken away;

Fig. 5 is a view similar to Fig. 1, but showing the tool in a raised position with a collar located at the top of a neck preliminary to the operation of assembling;

Fig. 6 is an enlarged view of the collar and neck shown in Fig. 5;

Fig. 7 is a view similar to Fig. 5 showing the pressure sleeve means engaged with the collar and exerting positive pressure thereon to telescope the collar over the neck; and

Fig. 8 is a view similar to Fig. 7, showing the collar fully telescoped over the neck and yieldingly held by the pressure sleeve at the time when the spinning head is about to commence the simultaneous spinning operation.

Similar numerals refer to similar parts throughout the various figures of the drawings.

The improved pressure spinning tool is generally indicated at 9 and includes a pressure sleeve holder 10, which may be removably mounted on or formed as a part of the non-rotating quill 11 of a drill press or other similar machine tool. The pressure sleeve holder 10 preferably has an outturned flange portion 12 and an elongated tubular portion 13. A pressure sleeve 14 is slidably and non-rotatably mounted on the pressure sleeve holder 10 and includes a flange portion 15, a preferably tubular portion 16 slidably mounted on portion 13, and an annular pressure foot 17 attached to or formed as a part of the lower or extended end of the sleeve portion 16.

A series of bolts 18 and lock nuts 19 are adjustably secured to flange member 12 to form an adjustable stop limiting the upward movement of pressure sleeve 14 on sleeve holder 10 (Fig. 1); and a similar series of bolts 20 and lock nuts 21 are secured to flange 15 and pass through openings in flange 12 to provide adjustable stop means limiting downward movement of pressure sleeve 14 on sleeve holder 10, and to maintain pressure sleeve 14 non-rotatable (Fig. 3).

If sleeve holder 10 is removably secured to quill 11, one or more set screws 22 may be provided for assembling said elements. Spring or yielding means, preferably a plurality of compression springs 23, react between flanges 12 and 15 to normally urge the pressure sleeve 14 in the extended position indicated in Fig. 5.

The improved pressure spinning tool 9 also includes a spinning head generally indicated at 24, which may be formed as a part of the rotatable machine tool spindle 25, or may be removably mounted thereon in the conventional manner shown. The spinning head 24 is provided with a spinning roll holder portion 26, located entirely within pressure sleeve 14; and holder

26 is provided with a plurality of apertures 27, in which spinning rolls 28 are journaled, preferably by radial needle bearings 29 and thrust ball bearings 30.

As shown, the axes of the spinning rolls are parallel with the axis of the spinning head 24 and rotatable spindle 25; and the curved outwardly, downwardly presented working surfaces 31 of the spinning rolls are located substantially entirely within the opening defined by the annular pressure foot 17.

The spinning rolls 28 and holder 26 may be maintained assembled to spinning head 24, as shown, by member 32 secured to spinning head 24 by bolt 33. Member 32 is formed with a preferably cylindric outer surface 34, which acts as a pilot for the improved pressure spinning tool. The spinning rolls 28 may be lubricated through aperture 35 in pressure sleeve 14, and oil holes 36 in spinning head 24.

In the manufacture of metallic containers embodying the integral threaded sheet metal neck bung opening construction of the Draper Patent No. 2,156,237, it is sometimes desired to telescope a flanged collar over and secure it to the threaded neck. In Fig. 6, a sheet metal container wall is indicated at 37, having an integral neck 38 threaded at 39, terminating in an unthreaded upstanding portion 40; and the collar to be secured thereto is indicated at 41, having an outturned flange at 42 at its upper end and an outturned fillet flange 43 at its lower end.

After the neck 38 has been threaded, the outer diameter of portion 40 is slightly larger than the outer diameters indicated at 44. On the other hand, the internal diameter of collar 41 adjacent flange 42, is slightly larger than the internal diameter thereof adjacent flange 43. Accordingly, in telescoping collar 41 over neck 38 for assembling the collar on the neck, a maximum resistance obtains during the first portion of the telescoping operation.

In assembling a collar 41 on neck 38 with the improved pressure spinning tool in one machine operation, sheet metal wall 37 is placed on a support plate 45 under pressure spinning tool 14, and collar 41 is placed on top of neck 38, as shown in Fig. 5. Machine tool quill 11 is then moved downward until pressure foot 17 engages collar flange 42, whereupon continued downward movement of quill 11 causes pressure sleeve 16 to yieldingly move upward relative to sleeve holder 10, (due to the resistance to telescoping between collar 41 and neck 38) until stop bolts 18 engage flange 15, as shown in Fig. 7, whereupon continued downward movement of quill 11 positively presses collar 41 onto neck 38.

When the collar is approximately halfway telescoped over neck 38, the resistance to telescoping is so relieved that the pressure of springs 23 becomes greater and pressure sleeve 14 yieldingly moves downward to snap the collar 41 into a seated position, as shown in Fig. 8. Collar 41 is now yieldingly held by pressure sleeve 14 in seated position and upon continued downward movement of quill 11, spinning rolls 28 carried by rotating spinning head 24 engage upstanding neck portion 40, roller spin an outturned flange or lip 46 on the end of neck 38 over the upper end of collar 41 until the position of the parts shown in Fig. 1 is reached, when the operation is completed.

At the completion of the operation, pressure sleeve 14 is again positively pressing collar 41 in

seated position coincident with the simultaneous final spinning of outturned lip 46. Thus, collar 41 is accurately located with respect to neck 38 and tightly secured thereto by a single machine operation of the improved pressure spinning tool.

Meanwhile, pilot 32 guides and centers the pressure spinning tool while the collar is yieldingly pressed on the neck and during the spinning of lip 46, as shown in Figs. 8 and 1.

The improved manner of securing the flanged collar 41 externally to the threaded bung opening neck 38 includes placing of collar 41 on top of neck 38, as shown in Fig. 5, then first yieldingly and thereafter positively pressing the collar 41 to telescope it downwardly over and seat it around collar 38, then yieldingly holding the collar 41 in seated position on the neck 38 while simultaneously spinning an outturned lip on flange 46 from the upstanding collar portion 40, and finally positively pressing the collar in accurately located seated position on the neck coincident with the simultaneous final spinning of the lip 46.

Accordingly, the improved pressure spinning tool, while providing for yieldingly pressing and holding the collar as the spinning operation progresses, also provides for positively pressing the collar onto the neck to insure the positioning of the collar sufficiently ahead of the beginning of spinning to prevent the spinning rolls from forcing a lip on the neck outward against the internal collar wall if the collar is not fully seated on the neck. This condition could occur if only yielding pressure were used to press the collar onto the neck and the yielding pressure was not greater than an unexpectedly developed resistance to telescoping the collar on the neck.

Accordingly, the improved metal spinning apparatus reduces the cost of metallic container construction by eliminating an operation, and the handling incident thereto, involved in securing a flanged collar to an integral threaded bung opening neck; provides for positively seating and accurately positioning and securing a collar on the neck by a single machine operation by alternately yieldingly and positively pressing the collar and simultaneously spinning a collar securing flange on the neck; and provides apparatus for accomplishing the above and other results, which may be removably attached to any one of a number of standard types of drill presses or other similar machine tools, or may be formed as an integral part of such machine tool.

In the foregoing description, certain terms have been used for brevity, clearness and understanding, but not unnecessary limitations are to be implied therefrom beyond the requirements of the prior art; because such words, in being used for descriptive purposes and not for the purpose of limitation, are intended to be broadly construed.

Moreover, the invention is not limited to the exact structures shown herein, because the sizes of the various parts may be varied to provide other structural embodiments without departing from the scope of the present invention.

Having now described the features of the invention, the construction, manufacture and use of a preferred form of the improved apparatus and the advantages and results obtained by the use of the same; the new and useful inventions, constructions and devices, and reasonable mechanical equivalents thereof obvious to those

skilled in the art, are set forth in the appended claims.

I claim:

1. In pressure spinning apparatus, a work support, a sleeve holder movable toward and away from said support, an external pressure sleeve non-rotatably mounted on said holder and provided with an annular work engaging surface for engagement with the work on said support, rotatable spinning means carried by said holder and mounted within said pressure sleeve, said spinning means having spinning rolls with work engaging surfaces normally located above and spaced from said annular work engaging surface, means slidably and yieldably mounting said sleeve on said holder for simultaneous movement of said sleeve and spinning means downward toward said support permitting the work engaging surfaces of the spinning rolls to approach the plane of the annular work engaging surface of the sleeve, and means for positively downwardly moving the sleeve with the spinning means when a predetermined amount of approach has occurred.
2. In pressure spinning apparatus for telescoping a flanged collar over and securing it to a tubular neck, a support for a neck and for the collar to be telescoped thereover and secured thereto, a non-rotatable pressure sleeve for telescopically pressing said collar onto said neck, yieldable means acting against said sleeve to resist axial movement of said sleeve while said sleeve holds said collar in seated position on said neck, and rotatable spinning means mounted within said pressure sleeve for spinning the upstanding neck outwardly over the collar while the collar is yieldingly held, said pressure sleeve being movable relative to said spinning means.
3. In pressure spinning apparatus, a work support, a pressure sleeve for engaging the work carried by said support, a pressure sleeve holder movable toward and away from said support, means for slidably and non-rotatably mounting said pressure sleeve on said holder, means yieldingly resisting movement of said sleeve with respect to holder, means on the holder for rigidly abutting said sleeve after a predetermined amount of movement thereof with respect to said holder, rotatable spinning means carried by the holder and mounted within said pressure sleeve, and the sleeve mounting means including means for positioning the spinning means against the work following the movement of said sleeve against the work.
4. In pressure spinning apparatus, a work support, a pressure sleeve for engaging the work carried by said support, a pressure sleeve holder movable toward and away from said support, means for non-rotatably and slidably mounting said sleeve on said holder, means yieldingly resisting the slidable movement of said sleeve on said holder, means on said holder for positively abutting said sleeve after a predetermined amount of movement thereof on said holder, rotatable spinning means carried by said holder and positioned within said pressure sleeve, a pilot on said spinning means for centering said sleeve and spinning means, and said sleeve mounting means including means for positioning the spinning means against the work following the movement of said sleeve against the work.

JOHN W. SHERA.
